LOCK MECHANISM

Charles J. Schell, Cincinnati, Ohio

Application June 14, 1938, Serial No. 213,643

8 Claims. (CL. 70—66)

The present invention relates to lock mechanisms, and more particularly locks of the type adapted for use on hand bags, brief cases and the like.

An object of the invention is to provide a small, compact locking mechanism which is mechanically and structurally simple yet positive in action.

A further object of the invention is to provide a lock of the type mentioned which is tamper or fool proof, and which can be unlocked only by a positive act on the part of the user.

A further object is to provide a lock mechanism the members of which cannot spring open unexpectedly while being subjected to the usual stresses and strains encountered in normal use.

Still a further object of the invention is to provide a lock mechanism having a central control key which controls the bolt bars which cooperatively engage latch members remotely spaced therefrom.

These and other objects are attained by the means described herein and disclosed in the accompanying drawing, in which:

Fig. 1 is a side view of a hand bag embodying the invention.

Fig. 2 is an end view of a hand bag embodying the invention, partly opened to reveal certain details thereof.

Fig. 3 is a side view of the invention with a side wall removed showing the relation of the various parts in "unlocked" position.

Fig. 4 is a view similar to Fig. 3 showing parts in "locking" and "locked" position, portions of a hand bag also being shown.

Fig. 5 is a side view, partly in section, of the bolt actuating mechanism forming a detail of the invention.

Fig. 6 is a top view of Fig. 5 on lines 4—4 showing the relation of parts when in "unlocked" position.

Fig. 7 is similar to Fig. 6 showing the relationship of parts when in "locked" position.

Fig. 8 is a side view of a key guide and bearing forming a detail of the invention.

Fig. 9 is a side view of a key member forming a detail of the invention.

Solely for the purpose of illustration, the present invention will be described in connection with a hand-bag or the like. In the manufacture of hand-bags and brief cases which comprise opposed side walls or pocket members suitably hinged together along an edge common to each, it is customary to provide locking or fastening means for securing and maintaining the edges opposite said hinges in a closed, abutting rela-

tionship whereby various and sundry articles may be housed within the resultant structure.

As shown in Fig. 2 a lock casing 10 is disposed outwardly of one opposed pocket member 11 of handbag B, while a keeper means 12 is carried on the opposite outer edge of the second pocket member 13. The top pocket members are suitably hinged along base member 14. A bolt casing 100 is disposed interiorly of pocket member 11 directly below lock casing 10 and in lateral alignment with the keeper means 12.

As shown in Figs. 3 and 4 a casing 100 comprises side walls 16, 17, 18 and 19, and a bottom plate 20, all of which may be formed from a single piece of sheet metal. Suitable openings as 21 and 22 are provided through wall 16 for the reception of suitable keepers 12, hereinafter more fully described.

A revolvable cam 27 is centrally disposed within said casing 100, said cam having diametrically aligned bolt actuating faces 28 and 29. Cam 27 is operated by means of cam shaft 30 (Fig. 5). Two opposed bolt members 23 and 24 are slidably mounted within said casing, one on either side of cam 27, each bolt member terminating in a protruding finger or cam follower as 25 and 26, said fingers being diagonally disposed relative to cam 27 as clearly shown in Figs. 3 and 4. The width of bolts 23 and 24 adjacent said cam are such as to provide a sliding contact between opposed side walls 16 and 18 whereby the cam follower fingers 25 and 26 are constrained to move in a linear path relative to said cam. The outer ends of bolts 23 and 24 terminate in hook-like members which hereafter will be referred to as bolt hooks 31 and 32. It should be noted that the overall width of each bolt tapers off from a point of maximum width adjacent cam 27 to a minimum width adjacent the bolt hooks, whereby the outer end of each bolt may be moved laterally between walls 16 and 18 about the point of maximum width which functions as a pivot for such motion. The outer ends of bolts 23 and 24 are constantly urged toward upper wall 16 by means of suitable flat springs 33 and 34 which are fastened to the bolts intermediate their ends by any suitable means such as recessed portions 35 and 36 provided in the lower face of each bolt 23 and 24, the free end of each spring bearing against lower wall 18, as shown. The bolt members are continually urged centerward of casing 100 toward cam 27 by means of coil springs 37 and 38 which fit within suitable apertures 39 and 40 stamped or cut through members 23 and 24 respectively. One end of

each spring bears against that end of its aperture adjacent cam 27, and the opposite end of each spring bears against a lip 41 punched from bottom plate 20, whereby the bolts are positively urged centerward relative to casing 100.

An indented bolt trip face 42 and 43 is provided in the outer end of each bolt adjacent, but centerward of the respective bolt hooks 31 and 32. Suitable retainer pins 46 and 47 extend from the bottom wall 20, adjacent the hooked end of each bolt. Said pins cooperate with notches as 44 and 45 and slots 48 and 49 provided in the outer ends of bolts 23 and 24 below bolt hooks 31 and 32 respectively. The relationship between the retainer pins 46 and 47, notches 44 and 45 and slots 48 and 49 is such that the pins and notches engage as shown in Fig. 3 when the bolts are in an "unlocked" position viz., the bolt hooks 31 and 32 being withdrawn from openings 21 and 22, the ends of said bolts are held in contact with the under side of upper wall 16 by springs 33 and 34 said bolts being continually subjected to the force of springs 37 and 38 which, but for the engagement between pins 46 and 47 and notches 44 and 45, would move the bolts centerward.

Bolts 23 and 24 are released to a "locked" position as shown in the right side of Fig. 4 by means of a lip 50 formed upon the keeper 12 at right angles thereto whereby a bolt hook engaging member is formed. The edge of each lip remote from pins 46 and 47 is bent outward whereby to form a bolt trip face engaging leg 51.

As shown in the left of Fig. 4, the entry of keeper 12 into the bolt casing 100 will cause the leg 51 thereof to contact the latch trip face 42 of bolt 23 whereby to depress the outer end of said bolt downward against the counter force of spring 33, whereby notch 44 is moved downward away from fixed pin 46. Further insertion of keeper 12 causes notch 44 to clear pin 46 whereby the bolt is instantly urged centerward by spring 37 to assume a relationship shown on the right side of Fig. 4. As the bolt is pulled centerward, as stated, the latch pin 32 engages lip 50 as shown. At this point it should be noted that each bolt may act independently of the other, whereby a safety feature is provided.

The bolt hook 32 and lip 50 will remain in "locked" relationship until bolt 24 is moved outward by means of cam 27, whereby bolt 24 will assume the tensioned unlocked position shown in Fig. 3.

Cam 27 is actuated by cam shaft 30 which comprises the free end of operator member 60 which is positioned on the outside of a handbag or the like. An operator locking mechanism is located between operator 60 and cam shaft 27, and comprises the casing 10 housing a laterally sliding lock plate 62 (Figs. 5, 6 and 7) having a key hole shaped aperture 63 extending centrally therethrough. The key hole aperture is so proportioned that the rectangular shank 64 of cam shaft 30 can freely rotate when positioned within the circular part of the key hole shaped aperture, as shown in Fig. 6, but said shank is secured against rotation when positioned within the rectangular part of aperture 63, as shown in Fig. 7. Adjacent one end of plate 62 and medially disposed therethrough is an elongated aperture 65. Adjacent said aperture and positioned along one edge of plate 62 are two spaced, upwardly extending legs 66 and 67. On the other end of plate 62 a pair of upwardly extending lugs 68 and 69 are struck on opposite sides thereof

as shown. A hairpin shaped spring 70 having long converging legs 71 and 72 is secured between lugs 68 and 69. Legs 71 and 72 of spring 70 exert a squeezing or compressing force upon 5 opposite faces of shank 64 whereby said shank is prevented from coming to rest in any position other than when the longer faces thereof are parallel with and between legs 71 and 72 whereby shank 64 is always properly positioned 10 so that lock plate 62 may be reciprocated.

Longitudinal movement is imparted to plate 62 by means of a key 80 having depending lug tipped legs 81 which are adapted to cooperate with the key receiving slots 82 of key guide and 15 bearing member 83 which is rotatably mounted as shown in Fig. 5, between the upper and lower plates of casing 10. A pin 84 extends through elongated aperture 65 of plate 62 as clearly shown in Figs. 5, 6, and 7. By turning a key 80 20 in a counter-clockwise direction, the lug lip 81 (Fig. 6) pushes against lug 66 thereby sliding the plate 62 to the left to assume a position as indicated in Fig. 7, whereby the key hole slot engages shank 64 thereby securing said shaft 25 from being rotated in either direction. Shank 64 is released by reversing the above procedure.

A top plate, not shown, for casing 100 is secured thereto in parallelism with bottom plate 20 by any suitable means such as by means of rivets which may be mounted through openings 90 formed when spring retaining lips 41 were struck from bottom plate 20. The entire casing may be fastened to one side of the handbag by suitable means as bolts or rivets through suitable apertures as 91. The lock casing 10 is secured to the outside of the handbag whereby cam shaft 30 is aligned with the cam shaft engaging aperture 92 of cam 27, as shown in Fig. 5. Casing 10 is secured to the wall of the handbag by means of suitable bolts or rivets (not shown) which cooperate with apertures 93.

The present invention discloses a positive acting, fool proof latching mechanism suitable for use on handbags and the like. The latch members 45 cannot become disengaged and spring apart from the latch retaining mechanism at a time other than when the operator desires, because the latch bolts are ever tensioned for locking position. To free the bolt hooks from keepers 50 requires the positive act of manually turning operator member 60 at least one half turn against the tension of springs 37 and 38. It should be noted that each bolt member is capable of latching independently of the other.

The present invention also presents a fool proof latching and locking means whereby handbags and the like may be securely locked. Once 55 the bolt hooks 31 and 32 have engaged their respective keeper members 12 it becomes impossible to separate these parts except in the manner just described. It is to be understood that the bolt members 23 and 24 may be made any desired length without departing from the spirit of the invention. The invention is described as 60 a latching locking mechanism for a handbag but it is not meant to limit application merely to handbags, but rather it shall include all those devices in which it is desired to latch or lock two sides together.

The foregoing detailed description has been given for clearness of understanding only and no unnecessary limitations should be understood therefrom, but it should be construed as broadly as possible in view of the prior art.

The invention disclosed herein, while adaptable

to various fields of use, is particularly serviceable in connection with handbags and smaller carrying cases, in that the primary or main holding members are not subjected to frictional contacts and movements for effecting locking and unlocking functions. Instead, a tripping action is relied upon. By reference to Fig. 4, it is evident that contact of legs 51 on primary holding lugs 12, and movement of the primary holding or latch pins 31 and 32, under the influence of pressure directed on the bolts 23 and 24, subjects neither the legs 50 nor lugs 12 nor pins 31, 32 to any frictional contact. Consequently the prime locking members are not subjected to any appreciable wear or possible distorting tensions, as is common in most varieties of locks provided for the indicated class of products.

What is claimed is:

1. In a fastening device of the class described comprising keeper members and locking means for retaining said keeper members, said locking means comprising a casing having apertures for the reception of said keeper members, a pair of oppositely extending, longitudinally reciprocable bolts having inner and outer ends, the inner ends of which make sliding contact with the walls of said casing and which terminate in diagonally opposed fingers, the outer free ends of said bolts being shiftable transversely of the axis of longitudinal reciprocation, the outer ends of said bolts being turned back toward the center of said casing to provide hooks having free ends each of which furnishes a keeper engaging hook, bolt retaining means disposed intermediate the ends of said bolts, means comprising a plurality of springs for constantly urging said bolts to a locked position, a bolt actuating cam centrally disposed intermediate the diagonally disposed fingers for longitudinally reciprocating said bolts whereby said bolts engage said retaining means which retain said bolts in a tensioned retracted unlocked condition, said bolts adapted to be disengaged from said retaining means by pressure applied directly to said bolts by said keeper members, and means for operating said cam.

2. In a lock mechanism including an outer casing having apertures therethrough, keeper members for introduction into said apertures, a pair of oppositely aligned bolts having outer free ends, and being reciprocable longitudinally along a common axis, the outer free end of each bolt being shiftable transversely of the axis of longitudinal reciprocation, the outer end of each bolt being turned back upon itself whereby to terminate in a bolt hook for engagement with said keeper members, means located intermediate the inner ends of said bolts for imparting an outward longitudinal movement to said bolts for positioning said bolt hooks at the outermost edge of said keeper member apertures and in an unlocked position out of engagement with said keeper members, means for yieldingly urging each of said bolts centerward of said casing to a keeper-engaging position of the hooks, and means for yieldingly urging the outer ends of said bolts transversely of their axis of longitudinal reciprocation for positioning the bolt hooks adjacent the under side of the keeper apertures, means for retaining said bolts in an unlocked position against the counter force continuously urging said bolts centerward, the outer ends of said bolts being adapted to be shifted transversely of their respective retaining means by a cooperating keeper member whereby said bolts are disengaged from said retaining means and instantly there-

after shot centerward to engage the hooks with said keeper members.

3. In a fastening device of the class described comprising keeper members and keeper latching means, said keeper latching means comprising a casing having apertures into which the keeper members are adapted to be introduced for engagement with said keeper latching means, and longitudinally reciprocable bolts having free outer ends shiftable transversely of the axis of longitudinal reciprocation, means for yieldingly urging said bolts to engage said free outer ends with said keeper members, and means for retaining said bolts in a tensioned, nonengaging position with respect to the keepers, said keepers each including a laterally extending lip disposed in substantial parallelism to the longitudinal axis of reciprocation of said bolts, one end of said lip terminating in a depending leg which contacts a bolt end when a keeper is inserted into one of said apertures and through which a transverse motion is imparted to a bolt for disengaging same from its retaining means, said keeper lips and projecting legs being so proportioned as to cause disengagement of said bolts from said retaining means after said keeper lips are below the plane of longitudinal reciprocation of said bolts, whereby said bolt ends will positively engage the upper side of said lips.

4. In a lock, the combination of bolts provided for longitudinal reciprocation and having free outer ends shiftable transversely of the axis of longitudinal reciprocation, yieldable means for normally urging the outer ends of said bolts to one side of said axis of longitudinal reciprocation and for simultaneously urging said bolt ends to a keeper engaging position, means for imparting longitudinal motion to said bolts and means engageable by said bolts when in extended position for retaining said bolts in an extended position, each of said bolts adapted to be tripped from said retaining means by being shifted transversely of said retaining means by insertion of a keeper against the bolt whereby said bolts are released for keeper engagement.

5. In combination with the side walls of a handbag or the like, of keeper members anchored to one wall thereof and keeper retaining means fastened to the other wall of said handbag in cooperative alignment with said keeper members, said keeper retaining means comprising a casing having keeper member receiving apertures, longitudinally slidable bolts having free outer keeper-engaging ends shiftable transversely of the axis of longitudinal reciprocation of the bolts, means comprising a plurality of springs for retaining the keeper-engaging ends of the bolts normally in engagement with the keeper members, means for moving said bolts to keeper releasing position, including a manually controlled operator member, and means positioned intermediate said operator member and said bolts for selectively locking said operator against manipulation.

6. In a fastening device of the class described comprising keeper members and keeper retaining means, said keeper retaining means comprising a casing having apertures into which the keeper members are adapted to fit, latching means in the casing comprising oppositely aligned longitudinally reciprocable bolts including free ends which are shiftable transversely of the axis of longitudinal reciprocation, trip means for retaining said bolts in tensioned unlocked position and responsive to pressure applied laterally to the bolts by the keeper members when inserted in the cas-

ing apertures for releasing said bolts from unlocked position to engage the keeper members, centrally disposed cam-like means for sliding said bolts longitudinally outward into tensioned unlocked position, and means operatively associated with said cam-like means for manual operation thereof.

7. A lock structure which comprises in combination, an elongated shallow housing having a bottom wall and side walls, one of which side walls includes apertures at a distance from the opposite ends of the housing for reception of a pair of keepers, a double action cam mounted for rotation at substantially the middle point of the lock housing in a plane parallel to the bottom wall thereof, a pair of elongated bolt members each slidably longitudinally within the housing wholly at opposite sides of the cam, said members having inner ends each contacting the cam whereby rotation of the cam projects the bolt members away from one another toward their respective ends of the housing, yielding means constantly urging the bolt members toward one another and against opposed areas of the cam, a U-turned outer end on each elongated bolt member, said ends both being directed toward the rotatable cam and toward one another, and disposed one each adjacent to a keeper aperture for movement with the bolt members inwardly toward the cam and into obstructing relationship relative to the keeper apertures, under the propelling influence of the yielding means aforesaid, trip means operative to retain the bolt members when projected apart by the cam a distance sufficient to cause both U-turned ends to clear the keeper apertures for entry of the keepers, and a pair of keepers to release the trip means and engage with the termini of the U-

shaped bolt member ends, upon insertion of the keepers into the housing apertures.

8. A lock structure which comprises in combination, an elongated shallow housing having a bottom wall and parallel side walls, one of which side walls includes apertures spaced from the opposite ends of the housing for reception of a pair of keepers, a manual bolt actuator located substantially midway of the ends of the housing, 10 a pair of elongated bolt members each of a thickness approximating the depth of the lock housing and adapted for reciprocation longitudinally within the housing wholly at opposite sides of the actuator, said members having inner ends 15 each contacting the actuator and being projectable thereby in opposite directions toward the respective ends of the housing occupied by the bolt members, yielding means constantly urging the bolt members toward one another and against 20 opposed areas of the actuator, a U-turned outer end on each elongated bolt member, said ends being both directed toward the actuator and toward one another, and disposed one each adjacent to a keeper aperture for movement with the bolt members inwardly toward the actuator and into obstructing relationship with the keeper apertures, under the propelling influence of the yielding means aforesaid, trip means operative to retain the bolt members when projected 25 apart by the actuator a distance sufficient to cause both U-turned ends to clear the keeper apertures for entry of keepers, and a pair of keepers to release the trip means and engage with the termini of the U-shaped bolt member ends, 30 upon insertion of the keepers into the housing apertures.

CHARLES J. SCHELL.
